GAME PLAYING BOARD

Forest Glenn Patrick Hagin, 610 Ridgedale Drive,
Garland, Tex.

Filed Nov. 4, 1964, Ser. No. 82,469

Term of patent 14 years

(Cl. D34—5)

Fig. 1

Fig. 2

FIGURE 1 is a view of one side of the game playing board embodying my new design; and

FIGURE 2 is a plan view of the opposite side of the game playing board.

The board is of a conventional thickness. The drawings are lined to indicate color. The dominant feature of my design resides in the portion shown in full lines. The series of circles on each side of the board are a part of the surface ornamentation.

I claim:

The ornamental design for a game playing board, substantially as shown and described.
